UNITED STATES PATENT OFFICE

168,369

COMBINED SALT AND PEPPER SHAKER

Akira Omoto, San Francisco, Calif.

Application September 12, 1952, Serial No. 21,436

Term of patent 14 years

(Cl. D44—22)

To all whom it may concern:

Be it known that I, Akira Omoto, a citizen of the United States, residing at San Francisco, county of San Francisco, and State of California, have invented a new, original, and ornamental Design for a Combined Salt and Pepper Shaker, of which the following is a specification, reference being had to the accompanying drawing, forming a part hereof.

Figure 1 is a front elevational view of a combined salt and pepper shaker, showing my new design;

Figure 2 is a side elevational view;

Figure 3 is a top plan view; and

Figure 4 is a bottom plan view.

I claim:

The ornamental design for a combined salt and pepper shaker, as shown.

AKIRA OMOTO.
